UNITED STATES PATENT OFFICE.

FRANZ TRINKS, OF BRUNSWICK, GERMANY.

CALCULATING-MACHINE.

1,075,073.

Specification of Letters Patent.

Patented Oct. 7, 1913.

Application filed January 4, 1913. Serial No. 740,206.

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Calculating-Machines, of which the following is a specification.

My invention relates to improvements in calculating machines, and more particularly in calculating machines of the class shown and described in the patents of the United States Nr. 1,040,059 previously granted to me October 1, 1911, and Nr. 952,257, 15 granted January 17, 1910 to Jahnz, in which setting disks are provided with radially shiftable teeth which are adapted to be set in operative positions by means of cam disks. Machines of this type are provided with a single registering mechanism, and where it was desired to perform continuous additions of products, each product was at first transmitted by means of the setting disks to the numeral wheels of the 20 registering mechanism, whereupon the setting disks were reset to zero. Then the numeral wheels were reset so as to transmit the product to the setting disks, and the carriage carrying the registering mechanism was shifted, so that the setting disks 25 were in position for coöperation with a different set of numeral wheels, and the value on the setting disks which represented the product was transmitted to the 30 said new set of numeral wheels. By repeating this method all the products were finally summed up in their set of numeral wheels. This method is simplified by setting the factors of the product from the 35 beginning on the two sets of setting disks, so that by a single revolution of the machine crank the product is produced on two sets of numeral wheels. The product is left in one of the sets of numeral wheels, 40 while it is erased from the other set, so that this set is again free to receive and display the new product, while at the same time the new product is added to the product which has been left from the foregoing 45 operation or operations on its set of numeral wheels. Thereby the products can be separately produced, and furthermore the sum of all the products is obtained by the same 50 operation. Preferably the two operations 55 which are thus simultaneously performed are carried out in such a way, that the

values are set on the one hand on the setting disks located at the right of the machine, and on the other hand on the setting disks located at the left of the machine, and preferably between the sets of setting disks a few setting disks are left which are not used at all, because thereby mistakes are more safely avoided.

One of the objects of the invention consists in so constructing the calculating machine, that the said simultaneous setting operations are performed in a convenient and reliable way, so that they can be performed with great speed and mistakes are 60 avoided.

With this object in view my invention consists in providing means whereby corresponding setting disks of both sets can be operatively connected, so that by setting 65 a value in one set of setting disks the same value appears in the other set.

In order that my invention be more clearly understood several examples embodying the same have been shown in the 70 accompanying drawings, in which the same letters of reference have been used in all the views to indicate corresponding parts.

In said drawing—Figure 1, is a vertical cross-section of the machine taken on the 75 line 1—1 of Fig. 2, Fig. 2, is a rear view of the machine shown in Fig. 1 with the rear wall of the casing and the registering mechanism removed, Fig. 3, is a cross-section showing a detail of the mechanism 80 shown in Figs. 1 and 2, Fig. 4, is a front view showing a modification of a detail of the machine shown in Figs. 1 and 2, Fig. 5, is a vertical cross-section similar to that shown in Fig. 1, and showing a modification 85 of the invention, Fig. 6, is a rear view of the modification shown in Fig. 5, in which the rear wall and the registering mechanism has been omitted, Fig. 7, is a vertical cross-section of a further modification 90 shown in Fig. 1, and showing a modification 95 of the invention, Fig. 8, is a rear view of Fig. 7 with the rear wall and registering mechanism removed. Fig. 9, is a detail view of a part shown in Figs. 7 and 8, Fig. 10, is a front view of a further modification, the cover 100 of the casing, the registering mechanism, and most of the setting disks being removed, and Fig. 11, is a vertical cross-section similar 105 to that shown in Figs. 1, 5 and 7, and showing a further modification.

Before describing those parts of the machine to which my invention more particu-

larly relates, I shall at first describe a calculating machine of known construction in which my invention is preferably embodied. But I wish it to be understood, that this 5 known type is described merely, because in my opinion it is necessary for a clear understanding of the invention, and that the invention is not limited to the use in the type of a calculating machine shown in the drawings.

As appears from Figs. 1 and 2, the calculating machine illustrated in the drawings comprises a horizontal shaft 1 which is adapted to be rotated by means of a crank 15 through the intermediary of gear wheels 2 and 3. To the said shaft setting disks 5 are rigidly secured which carry radially shiftable teeth 6 adapted to be shifted into or out of operative positions by means of 20 rotary cam disks 7. In front of the setting disks a carriage or slide 8 is located which is adapted to be shifted in a direction parallel to the shaft 1, and which provides a support for a shaft 10. On the latter a plurality of numeral wheels 9 are loosely mounted for independent rotation. Each of the numeral wheels is rigidly connected with a gear wheel 11 which is in engagement with a gear wheel 12. All the gear wheels 12 are 25 loosely mounted on a shaft 13, and they are located in the planes of the teeth 6 of the setting disks 5 and in such positions as to be adapted to be rotated thereby. Each of the numeral wheels 9 is acted upon by a locking pawl 14 which is adapted to lock the same in its positions, and the numbers made on the outer circumferences of the numeral wheels can be read through peep holes 19 made in the cover 20 of the casing. Between successive numeral wheels carrying 30 mechanism is provided which in the example shown in Figs. 1 and 2 consists of a lever 15 constructed in the form of a hammer and having a rocking support on a shaft 16 disposed parallel to the shaft 10. Each of the 35 numeral wheels is provided with a pin 17 which is adapted to engage the lever 15 and to rock the same, whenever the numeral wheel passes from the "nine" position to the "zero" position, or vice versa. Thereby the beveled face 15" of the lever 15 is brought into the path of a tooth 18 which is located on the co-operating setting disk 5 and is adapted to be rocked by the lever 15 40 laterally and into position for engagement with the intermediate gear wheel 12 connected with the numeral wheel of the next higher order. Thereby the said intermediate gear wheel and the numeral wheel connected therewith are advanced a distance corresponding to one value. After the tooth 18 has thus carried over the ten to the adjacent numeral wheel, the rocking lever 15 is returned into inoperative position by 45 means of a cam 21 secured to the setting disk

5. Ordinarily in machines of this type a further registering mechanism is provided on the carriage 8 and coaxially of the aforesaid main registering mechanism, and this subsidiary registering mechanism has the function to count the number of revolutions to the machine crank 4. In the machine shown in Fig. 1 this revolution counting mechanism is associated with the disks 9 as usual in accordance with my construction and arrangement of parts. It is operated from the shaft 1 of the setting mechanism by means of a single tooth 22 (Fig. 2) which according to the position of the carriage 8 advances a numeral wheel of the revolution counting mechanism which corresponds either to the units, the tens, the hundreds, etc., according to the position of the carriage 8, as has been described more in detail with reference to Fig. 1 of my aforesaid Patent Nr. 1,040,059. The numeral wheels, and if necessary the revolutions counting mechanism, are provided with resetting mechanism. As shown, the resetting mechanism is provided by the shaft 10 which, as is shown in detail in Fig. 3, is equipped at its outer end with a thumb nut 23 for rotating the same, and with radial pins 24 one for each of the numeral wheels and enclosed within a concentric cavity of the latter. The said pins are adapted to engage noses 25 provided on the numeral wheels, for which purpose the shaft 10 is shifted, during the first part of its rotation by the thumb nut 23, by means of a cam face 26 and against the action of a spring 27. To prevent the numeral wheels from taking part in this shifting movement, short sleeves 28 are interposed between the same.

Referring now to those parts of the calculating machine to which my invention more particularly relates, reference will at first be had to Figs. 1 and 2, which show one embodiment of the invention. As appears from the said figures, a frame 29 has a rocking support on a shaft 31 mounted on brackets 30. On the said frame shafts 33 are mounted for rotation, and the number of the said shafts is equal to the number of setting disks provided in each of the sectional setting mechanisms. On each of the shafts two gear wheels 34 and 35 are rigidly mounted, one of which, 34, is in position for engagement with spur gears 7' connected with one of the setting disks of one set, while the other one, 35, is in position for engagement with spur gears 7" connected with the corresponding setting disk 7 of the other set. The frame 29 can be rocked by means of a handle 32 with the gear wheels 34 and 35 of all the shafts 33 in or out of engagement with the spur gears 7' and 7" respectively. If now the frame 29 is rocked with its gear wheels 34 and 35 in operative positions, and a value is set in the right hand set of set- 125

ting disks, the same value is simultaneously set on the setting disks of the left hand set. In order that it is not necessary during the setting operation to hold the frame 29 by hand, I prefer to provide locking means for the frame which as shown consist of a spring actuated locking pawl 36.

In Fig. 4, I have shown a modification of the construction of the mechanism connecting corresponding setting disks of both sets.

- 10 In this example the gear wheels are located out of the plane of the spur gears 7' and 7'' and they are adapted to be brought into cooperation with the said spur gears by being shifted in a direction parallel to the shaft 1.
- 15 In the example shown in Fig. 4 the frame 29' which carries the gear wheels 34 and 35 is shiftable by means of upper and lower guide members 37 and 38.

20 In many calculations, for example in rebate calculations, it is desirable to set in one group of setting disks a certain number, and simultaneously in the other group a number which complements the first number to the next higher power of ten. For example, if 25 in one of the groups the number 768 is set, the other group should receive the number 232, so that the sum of both numbers is 1000. One of the objects of the invention is to so 30 construct the calculating machine, that the said values, that is the main or basic value and its complementary value, are set by means of a single operation. With this object in view the gear wheels, which, as in 35 the examples described with reference to Figs. 1 to 4, connect corresponding setting disks of both groups with each other, are connected with each other in such a way, that the said gear wheels rotate in opposite directions. This may be done for example 40 by providing additional gear wheels intermediate the said corresponding gear wheels, by means of which the rotation of the setting disks of one group is reversed as to the corresponding setting disks of the other group. In this case the setting disks on 45 which the main basic number is set are at first set in their zero positions and thereupon shifted in the ascending order of their numbers, until the desired number is reached, so that the setting disks which are designed 50 to receive the complementary numbers and are at first in their nine positions are turned in the descending order of the numbers.

55 Before further describing my new method I deem it best to first describe mechanism whereby the method may be carried out.

As appears from Figs. 5 and 6, a frame 60 40 has a rocking support on a shaft 39, and it is adapted to be rocked by means of a handle 41. At one side the said frame carries shafts 42 each of which has gear wheels 46 and 44 secured thereto. At the opposite 65 side rotary shafts 43 are mounted on the

frame, and each of the said shafts has gear wheels 45 and 47 secured thereto. The gear wheels 44 and 45 of corresponding shafts 42 and 43 are in engagement with each other, and corresponding gear wheels 46 and 47 are connected with corresponding setting disks of both sets. The frame 40 can be locked in operative position by any preferred means. If the machine is designed to be used only for calculations of one character, it may be rigidly secured to the machine frame. For performing the aforesaid double calculations, the setting disks of one set, which are designed to have the complementary numbers set thereon, are at first set in their nine positions, with the exception of the setting disk which receives the digit of the lowest place of the number to be set. This setting disk is set on the next value beyond the nine position, that is the ten position. Should at the last place or places of the number be the zero, the corresponding setting disks are set in their zero positions. All the setting disks corresponding to the main or basic numbers are set in their zero positions. Now the rocking frame 40 is rocked into operative position, whereupon the machine is ready for use. The basic number is now set on its setting disks which have before been set on their zero positions, respectively. Thereby the setting disks of the other set are simultaneously set from their nine and ten positions to the numbers which are the complementary numbers of the basic number. If now the machine 90 is 95 operated in the usual way, the values set on the sets of setting disks are transmitted to the numeral wheels. To understand the method, it may be assumed that the number 7680 and its complementary number 2320 is to be set on the setting mechanism. The setting disk which corresponds to the zero is placed in its zero position, and it is not turned at all, so that also the corresponding disk remains in its zero position. In the complementary group the setting disk 100 which corresponds to the digit 8 has been placed in its ten position, and it is turned backward into its 2 position, that is a distance which corresponds to eight units. 105 These eight units are transmitted to the corresponding setting disk of the other group, which is thereby set from its zero position to its eight position. The number 6 is now 110 set on the third setting disk by turning the third complementary disk from its nine position into its three position, that is at an angle which corresponds to six values. These 115 six values are again transmitted to the other group of setting disks, so that the third setting disk is turned six values out of its zero position and shows the number six. In a similar way the numbers seven and two are placed on the setting disks. Therefore I have in one set of setting disks the number 120 125 130

7680, and in the other set the number 2320, the sum of which numbers is 10000.

In Figs. 7 and 8 I have shown an example in which at will calculations of the character described with reference to Figs. 1 to 2, or calculations of the character described with reference to Figs. 5 and 6 may be performed. For this purpose reversing means are included in the mechanism connecting corresponding setting disks. The mechanism connecting corresponding setting disks is similar to the mechanism described with reference to Figs. 5 and 6. Rigidly mounted on a shaft 53 is a gear wheel 52 which is in engagement with one of the setting disks 7. At its opposite end the said shaft carries a sleeve 55 on which gear wheels 48 and 51 are mounted, and which is longitudinally slidable on the shaft but takes part in its rotation. On a shaft 54 a sleeve 56 is longitudinally slidable which has gear wheels 49 and 50 rigidly mounted thereon. The sleeves 55 and 56 are connected with each other by a member 57 engaging in circumferential grooves of the said sleeves. In the position shown in Fig. 8 the movement of one of the setting disks is transmitted to the other one through the intermediary of the gear wheels 48, 49, and 50, so that the movement is reversed, and the calculation described with reference to Figs. 5 and 6 is performed. When the sleeves 55 and 56 are shifted to the left, the gear wheel 50 and the setting disk get out of engagement with one another, and the gear wheel 51 gets in direct engagement with the gear wheel connected with the setting disk, so that the movement from one setting disk to the other one is transmitted in a positive sense.

In Fig. 9 I have shown means whereby all the members 57 coöperating with pairs of setting disks can simultaneously be shifted. For this purpose all the members 57 are connected by screws or rivets 58 with a slide 59 which at its ends carries pins 60 and 61 engaging in horizontal slots 62 and 63 made in the rear wall 65 of the casing of the machine. To the slide a handle 64 is secured which projects through the rear wall 65.

In Fig. 10 I have shown mechanism whereby the gear wheels and the coöperating cam and setting disks are automatically thrown out of operation when the machine crank is being operated. Thereby the operation of the machine is made more simple. For the matter of clearness only two coöperating setting disks 7, 7 and one pair of coupling gear wheels 66 and 67 mounted on a common shaft 68 have been shown. The said shaft is mounted on a frame 69, and it is under the action of a spring 70 which tends to shift the same in the direction from right to left. A lever 71 and a longitudinally shiftable rod 72 normally hold the

shaft 68 in coupling position against the action of the spring 70. The rod 72 is locked in coupling position by the machine crank 73 which is normally in the path of the said rod. When the crank is turned, or its spring actuated handle 74 is shifted from the left to the right or in the direction of the arrow 75, as is known in the art, the rod 72 is forced to the right and the spring 70 throws the gear wheels 66 and 67 out of engagement with the setting disks 7.

In Fig. 11, I have shown a further example in which the setting or cam disks 7 which are engaged by the coupling gear wheels 76, 77 are provided about the whole 80 of their circumferences with teeth 78. In this case, when the crank is being rotated, the coupling gear wheels 76 and 77 take part in such rotation and they remain in constant engagement with the setting or cam disks 7. 85

While in describing the invention reference has been made to particular embodiments thereof which in my opinion serve the purpose best, I wish it to be understood that my invention is not limited to the constructions shown in the drawings. For example instead of the means for automatically throwing the mechanism intermediate the setting disks out of operation other known or preferred means may be provided. 90 I also wish it to be understood, that means for disconnecting the corresponding setting disks may also be provided in machines of the construction shown in Figs. 1 to 4 in which the gear wheels are mounted on rocking frames. 100

My invention is not limited to such machines in which the values are set on rotary setting disks, but it may also be used in other machines, such for example as those shown in the United States patent to Jahnz, Nr. 952,257, in which the values are set on setting slides. 105

I claim herein as my invention:

1. In a calculating machine, the combination with setting members arranged in sets in different portions of the machine, and registering members coöperating therewith, of mechanism to connect corresponding setting members for common operation. 110

2. In a calculating machine, the combination with setting members arranged in sets in different portions of the machine, and registering members coöperating therewith, of mechanism adapted to be thrown out of 120 operation to connect corresponding setting members for common operation.

3. In a calculating machine, the combination with setting members arranged in sets in different portions of the machine, and 125 registering members coöperating therewith, of mechanism to connect corresponding setting members for common operation in opposite directions.

4. In a calculating machine, the combina- 130

tion with setting members arranged in sets in different portions of the machine, and registering members coöperating therewith, of mechanism adapted to be thrown out of 5 operation to connect corresponding setting members for common operation in opposite directions.

5. In a calculating machine, the combination with setting members arranged in sets in different portions of the machine, and registering members coöperating therewith, of mechanism to connect corresponding setting members for common operation, said mechanism being adapted for operation in 10 both directions.

6. In a calculating machine, the combination with setting members arranged in sets in different portions of the machine, and registering members coöperating therewith, of mechanism adapted to be thrown out of 20 operation to connect corresponding setting members for common operation, said mechanism being adapted for operation in both directions.

7. In a calculating machine, the combination with setting members, and registering members coöperating therewith, of mechanism to connect corresponding setting members for common operation and means automatically operated upon registering operation 25 of the setting members to throw said mechanism out of operative position.

8. In a calculating machine, the combination with setting members, and registering

members coöperating therewith, of mechanism to connect corresponding setting members for common operation in opposite directions and means automatically operated upon registering operation of the setting members to throw said mechanism out of 35 operative position.

9. In a calculating machine, the combination with setting members, and registering members coöperating therewith, of mechanism to connect corresponding setting members for common operation, said mechanism being adapted for operation in both directions, and means automatically operated 40 upon registering operation of the setting members to throw said mechanism out of 45 operative position.

10. In a calculating machine, the combination with setting members arranged in sets in different portions of the machine, and registering members coöperating therewith, of 50 gears connecting corresponding setting members for common operation, the gears directly connected with said setting members extending over the whole length 55 of the path of the setting members.

In testimony whereof I have hereunto set my hand in presence of two subscribing witnesses.

FRANZ TRINKS.
